UNITED STATES PATENT OFFICE.

ALBIN C. WREDE AND DAVID R. SAUNDERS, OF HOUSTON, TEXAS, ASSIGNORS
OF ONE-THIRD TO JEFFERSON N. MILLER AND GEORGE KIDD, OF SAME
PLACE.

EXTENSION CAR-STEP.

SPECIFICATION forming part of Letters Patent No. 630,764, dated August 8, 1899.

Application filed February 7, 1899. Serial No. 704,833. (No model.)

To all whom it may concern:

Be it known that we, ALBIN C. WREDE and DAVID R. SAUNDERS, citizens of the United States, residing at Houston, in the county of 5 Harris and State of Texas, have invented a new and useful Extension Car-Step, of which the following is a specification.

The invention relates to improvements in extension car-steps.

10 The object of the present invention is to improve the construction of extension car-steps and to provide a simple, inexpensive, and efficient one adapted for use on street-cars and railway-coaches and capable of being readily operated to extend it beyond the permanent car-steps and to fold it compactly beneath the same.

15 A further object of the invention is to provide a simple and efficient device adapted for holding the step in its extended and folded positions and to provide a cushion to prevent the extension-step from being injured should it come in contact with an elevated platform.

The invention consists in the construction 20 and novel combination and arrangement of parts, as hereinafter fully described, illustrated in the accompanying drawings, and pointed out in the claims hereto appended.

In the drawings, Figure 1 is a perspective 25 view of an extension-step constructed in accordance with this invention and shown applied to a car, the step being in its extended position. Fig. 2 is a side elevation of the same, the step being folded. Fig. 3 is a vertical sectional view of the same. Fig. 4 is a detail view of the friction device. Fig. 5 is a longitudinal sectional view of the extension-step, illustrating the manner of mounting the cushion.

30 Like numerals of reference designate corresponding parts in all the figures of the drawings.

1 designates a horizontal rock-shaft journaled in suitable bearings 2 at the back of 35 car-steps 3 and provided between its ends with a pair of arms 4, which are connected with rearwardly-extending arms 5 of an extension-step 6, and the latter is suspended from the front of the lowermost car-step by 40 links 7, whereby when the horizontal rock-

shaft is partially rotated to swing its arms 4 upward and downward the extension-step will be carried inward and outward to arrange it in its folded position beneath the lowermost car-step and to extend it to form a continuation of those steps. The arms 5 of the extension-step consist of rods having their lower ends bent at an angle and secured to the lower face of the extension-step 6, and their upper ends are hinged to the arms 4 by a 45 knuckle-joint, the arms 5 being preferably bifurcated and the arms 4 being reduced to fit in such bifurcations. The links 7, which are pivoted at their upper ends to the bottom of the car-steps, are similarly connected to 50 the extension-step at the rear edge thereof, being preferably formed integral with a pintle-rod 8, forming with the same a swinging frame for supporting the extension-step. The pintle-rod 8 passes through perforations or 55 eyes of plates 9, which are secured to the end edges of the extension-step and which project beyond the rear edge of the same.

The outer end of the rock-shaft is provided with an operating-arm 10, forming a handle 60 and adapted to be oscillated to swing the extension-step outward and inward, and it is provided with a weight 11 and is arranged to swing to opposite sides of the rock-shaft, whereby it is adapted to lock the step 6 in its 65 extended and folded positions. When the extension-step is folded, the weight is at its lowermost position, and there is no liability of it accidentally swinging upward and permitting the step to be projected outward 70 when a car is in motion, and in order to prevent absolutely any vibration of a car affecting the rock-shaft the latter is provided with a lug 11^a, arranged adjacent to its outer end, 75 engaging a spring 12. The lug or arm is tapering, as shown, and its extremity is engaged by the lower free end of the spring when the step is folded. The upper end of the spring is secured to an L-shaped plate 13, which is attached to the outer side of the car- 80 steps, as shown, and the inner end of the lug or arm forms a shoulder, which is engaged by the spring when the step is extended to prevent the same from accidentally folding.

85 The plates 9 are provided at their front 90

ends with depending projections or lugs 14, having slots 15 to receive the ends of the spring 16, arranged beneath the step and bowed to form a cushion, whereby the step is 5 prevented from being injured should it come in contact with a high platform when it is 10 swung downward and outward. The ends of the spring 16 play freely through the slots 15 and are provided at the outer faces of the 15 plates with suitable stops 17 to prevent them from becoming disengaged from the plates 9.

The invention has the following advantages: The folding step, which is simple and inexpensive in construction, is applicable to 15 street-cars and railway passenger-coaches and is capable of being readily extended to its operative position and folded beneath the car-steps out of the way when it is not needed. The 20 operating-arm of the rock-shaft serves to hold the step in both positions, and the friction device prevents any vibration of the car from 25 affecting the position of the parts. The cushion at the bottom of the extension-step is adapted to prevent the same from being injured should it be thrown outward into contact with a high platform.

Changes in the form, proportion, and minor details of construction may be resorted to without departing from the spirit or sacrificing any of the advantages of this invention, 30 such as employing a spring, rubber, or other form of cushion between the extension-step and the permanent steps to prevent the former from vibrating when a train is in motion.

35 What we claim is—

1. The combination with the permanent steps of a car, of a rock-shaft mounted thereon and provided with crank-arms, means for rotating said rock-shaft, means for holding 40 said shaft in the position to which it may be turned, an extension-step, a pintle-rod journaled on the rear edge of the extension-step, links extending upward from the ends of said pintle-rod and having their upper ends pivoted to the bottom of the car-steps, and upwardly and rearwardly extending arms secured to the bottom of the extension-step near the ends of the same and having their upper ends pivoted to the ends of the crank-arm of 45 the rock-shaft, substantially as described.

2. In a device of the class described, the

combination of an extension-step, of a rock-shaft connected with the same and adapted to swing the step inward and outward, a lug carried by the rock-shaft, and a spring engaging the lug and adapted to hold the rock-shaft against movement, substantially as described. 55

3. In a device of the class described, the combination with the permanent steps of a car, of a rock-shaft journaled in suitable bearings on the car, an extension-step provided with links and suspended from the car-steps, and arms connected together and mounted respectively on the step and on the rock-shaft, a lug carried by the rock-shaft, a spring engaging the lug and adapted to hold the rock-shaft against movement, and a weighted arm carried by the rock-shaft and adapted to hold the extension-step in either of its positions, substantially as described. 60 65 70

4. In a device of the class described, an extension-step provided at its lower face with a cushion arranged to engage a platform to prevent the extension-step from being injured, substantially as described. 75

5. In a device of the class described, an extension-step provided at its bottom with a bowed spring, having its ends slidingly connected with the step, substantially as and for 80 the purpose described.

6. In a device of the class described, the combination of an extension-step provided at opposite sides with depending slotted plates, and a spring having its ends extended 85 through the slots of the plates and provided beyond the same with stops, said spring being bowed between the plates and arranged to form a cushion, substantially as described.

7. In a device of the class described, the 90 combination of a permanent step, an extension-step mounted thereon, and a cushion for the extension-step, substantially as described.

In testimony that we claim the foregoing as our own we have hereto affixed our signatures 95 in the presence of two witnesses.

ALBIN C. WREDE.
DAVID R. SAUNDERS.
